(57) **CLAIM**

The ornamental design for hand held internet browser with folding keyboard, as shown and described.

DESCRIPTION

FIG. 1 is a right side perspective view of a hand held internet browser with folding keyboard having its display housing open and the keyboard in an unfolded position;

FIG. 2 is a rear view thereof;

FIG. 3 is a front view thereof;

FIG. 4 is a right side view thereof;

FIG. 5 is a left side view thereof;

FIG. 6 is a bottom view thereof;

FIG. 7 is a front elevational view thereof;

FIG. 8 is a front elevational view of a hand held internet browser with folding keyboard having its display housing open and the keyboard in a partially unfolded position;

FIG. 9 is a front elevational view of a hand held internet browser with folding keyboard having its display housing open and the keyboard in a folded position;

FIG. 10 is a top view of a hand held internet browser with folding keyboard having the keyboard in the folded position and its display housing closed;

FIG. 11 is a front view thereof;

FIG. 12 is a rear view thereof;

FIG. 13 is a left side view thereof;

FIG. 14 is a right side view thereof; and,

FIG. 15 is a bottom view thereof.

The broken lines are shown in the views for illustrative purposes only and form no part of the claimed design.
